UNITED STATES PATENT OFFICE.

HENRY E. LODL, OF MISHICOT, WISCONSIN.

WIRE-CUTTER FOR GUNS.

1,220,355.

Specification of Letters Patent. Patented Mar. 27, 1917.

Application filed July 22, 1916. Serial No. 110,767.

To all whom it may concern:

Be it known that I, HENRY E. LODL, a citizen of the United States, residing at Mishicot, in the county of Manitowoc and State of Wisconsin, have invented certain new and useful Improvements in Wire-Cutters for Guns; and I do hereby declare the following to be a full, clear, and exact description of the invention, such as will enable others skilled in the art to which it appertains to make and use the same.

This invention has for one of its objects the provision of a device of this character, which shall be simple, durable and efficient, and which may be manufactured and sold at a comparatively low cost.

Another object of this invention is to provide a base having cutting means thereon and operated by a lever, whereby a wire may be readily severed by operating the lever.

A further object of this invention is to provide a stationary blade and a removable blade connected to the lever, whereby upon moving the lever, the movable blade will slide into engagement with the stationary blade and sever the wire placed between the blades.

A still further object of this invention is the provision of means for detachably securing the base to a barrel of a gun, so that the device may be readily removed and replaced on the barrel when desired.

With these and other objects in view, as will become more apparent as the description proceeds, the invention consists in certain novel features of construction, combination and arrangement of parts as will be hereinafter more fully described and claimed.

For a complete understanding of my invention, reference will be had to the following description and accompanying drawing, in which:—

Figure 1 is a side elevation partly in section, of a wire cutter, constructed in accordance with my invention,

Fig. 2 is a bottom plan view of the same, and

Fig. 3 is a sectional view taken on the line 3—3 of Fig. 1.

Referring in detail to the drawing, the numeral 1 indicates a base, having secured to its upper face a plurality of substantially U-shaped clamps 2 which surround the barrel 3 of a gun. Suitable bolts 4 secure the

free ends of the U-shaped clamps together as clearly illustrated in Fig. 3, providing means whereby the base may be readily applied to and removed from the barrel 3 when desired. The lower forward face of the base 1 is slotted as illustrated at 5, said slot being in communication with a guide way 6 formed within the base adjacent the rear end thereof. A blade 7 is formed upon the lower face of the base 1 and has a cutting edge 8. A movable blade 9 having an arm 10 formed thereon and extending at right angles is received within the guide way 6, allowing the movable blade 9 to depend downwardly through the slot 5 of the base. A coil spring 11 is secured to the forward end of the base 1 and to the movable blade 9 for normally holding the movable blade 9 adjacent the forward end of the base. The movable blade has a cutting edge 12.

Pivoted to the rear end of the base 1 is a lever 13 having an extension 14 formed thereon to which are pivotally secured a pair of spaced connecting links 15 which are in turn pivotally secured upon each side of the movable blade 9 as illustrated at 16, for moving the movable blade toward and from the stationary blade 7 to sever wire.

In operation, when desiring to cut a strand of wire, the wire is placed between the cutting edges 8 and 12 of the blades 7 and 9 and by moving the lever 13 upon its pivot in the direction of the barrel 3 as illustrated in dotted lines of Fig. 1, the movable blade 9 will slide within the base, causing the cutting edge 12 thereof to engage with the cutting edge 8 of the stationary blade 7 thereby severing the wire.

While I have shown and described the preferred embodiment of my invention, it will be understood that minor changes in construction, combination and arrangement of parts may be made without departing from the spirit and scope of the invention as claimed.

Having thus described my invention, what I claim is:—

1. A wire cutter for guns comprising a base, clamps secured to the base for attaching the base to the barrel of a gun, said base having a slot in its forward end and a guide way in communication with the slot adjacent its rearward end, a blade formed on the base and having a cutting edge, a movable blade carried within the guide way

and depending downwardly through the slot, and means connected to the movable blade for moving the movable blade into an engagement with the stationary blade to sever a strand of wire.

2. A wire cutter for guns comprising a base, means for securing the base to the barrel of a gun, said base having a slot in its forward end and a guide way adjacent its rear end and in communication with the slot, a stationary blade formed on the base, a movable blade extending upwardly within the slot, an arm formed on the upper end

of the movable blade and slidably received within the guide way, a lever pivoted to the base, a pair of relatively spaced links pivoted to the lever and to each side of the movable blade for sliding the movable blade into an engagement with the stationary blade to sever a strand of wire.

In testimony whereof I affix my signature in presence of two witnesses.

HENRY E. LODL.
